JACK

George Stephen Whitehead, St. John, New
Brunswick, Canada

Application October 19, 1933, Serial No. 694,305

2 Claims. (Cl. 254—126)

This invention relates to jacks, and it is the object of the invention to provide a jack in which the lifting block may be lowered to within a very short distance from the ground and to provide moreover in this type of jack, a construction which contains few parts and will not easily get out of order.

In previously known jacks of the general type according to this invention the connections between the travellers and the lifting block have been complicated and in many respects inefficient. One of the main disadvantages of prior art constructions has been that the connecting members between the travellers and the lifting block have borne on pivots extending through the travellers and on pivots extending through the lifting block, tending in this way to exert a shearing action which increases with an increase in pressure on the lifting block. This action often results in parts becoming disaligned and in the jack becoming difficult of operation.

According to this invention a jack provided with a rotatable actuating member in the form of a double oppositely screw threaded shaft and with travellers mounted on this shaft and adapted to be moved towards each other upon its rotation in one direction, has a lifting block and members extending between the travellers and the lifting block and bearing directly and only thereupon. In the form of construction shown, the bearing surface on the travellers and on the lifting block extend over the entire width of these parts, the bearing surfaces on the travellers facing each other and those on the lifting block being on opposite sides thereof. The connecting members having bearing surfaces formed to coat with the surfaces on the travellers and lifting block and are of channel formation so that in their lower position they will partially enclose the actuating shaft. The bearing surfaces on the lifting block, may if desired, be made to extend over arcs of at the most 180° so as to render the block capable of being disengaged from the connecting members by simply being lifted up, in which case the connecting members will drop down to such a position that their tops are parallel with the base of the device.

In the drawing:—

Figure 1 is a partly sectional side elevation of the device in lowered position;

Figure 2 is a section along the line 2—2 of Figure 1;

Figure 3 is a section along the line 3—3 of Figure 1;

Figure 4 is a side elevation of one of the connection members;

Figure 5 is a side elevation of the lifting block;

Figure 6 is a side elevation of one of the travellers;

Figure 7 is a side elevation of a modified form of the lifting block having a plurality of gripping teeth on its upper face; and

Figure 8 is a further modified form of the lifting block.

In the form shown in Figures 1 to 6 inclusive, the jack comprises a base A including a bottom portion 1, end portions 2, side portions 3, and short top portions 4. The center of the base is attached to a supporting block 5 for the rotatable actuating member 6, the block being held in position on the base by bolts 7. The actuating member 6 comprises left and right hand screw threaded portions 8 and 8a respectively, and its end is squared as at 9, so that it may be rotated by any suitable form of arrangement.

Mounted on the left and right hand screw threaded portions 8 and 8a of the actuating member 6, are travellers 10 and 11 respectively, each formed with an upstanding hook-like projection 12, the interior of which is shaped to form a bearing surface 13, as shown in Figure 6. The lifting block 14 is formed with two bearing surfaces 15 facing in opposite directions and formed, if desired, to extend over arcs of not more than 180°. Extending between the travellers 10 and 11 and the lifting block 14 are members 16 of channel formation having their open side downwardly directed. These members are formed at one end with upstanding portions 17 of cylindrical form cooperating with the bearing surfaces 13 of the travellers and at their other end with outstanding portions 18 of cylindrical form cooperating with the bearing surfaces 15 in the lifting block. It is to be noted that the members 16 bear directly and only upon the travellers and upon the lifting block and not on pivots set in these latter. In this way the undesirable shearing action referred to in connection with prior art constructions is avoided. In the form of construction shown, the channel members, travellers and lifting block are of the same width, and therefore contact with each other over their entire width. This is the most natural way of making the device, but it is obvious that any of these parts could be made wider than the others if desired.

In my device, the bearing surfaces 15 on the block 14 are generally formed so as to grip the portions 18 of the member 16, that is, they are formed to extend over arcs of more than 180°. If, however, the size of space in which the jack is to be stored is a factor, then the surfaces 15 may be made to extend over not more than 180°. By this construction the lifting block 14 may be removed when the jack is not in use simply by lifting it up, as its bearing surfaces do not grip the portions 18. When the lifting block is removed the channel members drop down till they lie parallel with the bottom 1 of the base. In this way the device may be put away in a very small space.

It will be noted in the structure shown in Figures 1 and 5, the lifting block is provided with overhanging ledge portions 14' which are adapted to overhang the bearings 15 and provide an efficient rest for the lifting block 14 upon the bearings 15.

In Figure 7 there is shown a lifting block 14a of similar construction to the lifting block 14, which block 14a is provided with bearing surfaces 15a upon its side of 180°. The upper face of the lifting block 14a is provided with gripping teeth 17' to facilitate the gripping of an article to be lifted by the jack.

In the modified form shown in Figure 8, the lifting block 18a is illustrated having bearing sockets of 180° only, indicated by the numeral 19 upon the sides thereof. In this structure, no material overhanging ledge portion is illustrated such as is defined in Figures 5 and 7.

The sockets 13 in members 10 and 11 provide a circular bearing of 180° at all elevations and also a bearing in plan the full width of the lifting members 16. This feature offers advantage over pivotal bearings in having much less friction per square inch, eliminating any direct shear and due to the increased area of longitudinal bearing surfaces of pivotal connections insures more stability when the jack is in elevation.

Various modifications may be made in this invention without departing from the spirit thereof or the scope of the claims, and therefore the exact forms are to be taken as illustrative only and not in a limiting sense, and it is desired that only such limitations shall be placed thereon as are disclosed in the prior art or are set forth in the accompanying claims.

What I claim as my invention is:—

1. A jack comprising an elongated base having side walls and end walls, a bearing block secured in said base midway the length thereof, an actuating screw extending longitudinally in said base with its intermediate portion journaled through said bearing block and its end portions journaled through the end walls of the base, one end portion being extended and adapted for engagement by a turning element, the portions of said screw between said block and opposite ends of said base being oppositely threaded, travelers in end portions of said base fitting snugly between side walls thereof and formed with threaded bores receiving the threaded portions of said screw whereby the travelers will be moved longitudinally in the base when the screw is rotated, each traveler having a tongue rising therefrom and curved longitudinally to overhang the traveler, said tongue corresponding in width to the traveler and extending towards the inner end of the traveler and defining a semicircular bearing socket between the tongue and upper face of the traveler, a lifting block disposed over said bearing block, and having each end recessed for its full width to form a semicircular bearing socket and an outstanding tongue along the upper portion thereof, and links extending longitudinally of said base between the lifting block and travelers and having depending side flanges extending into the base in contacting engagement with side walls thereof, said links each having at its outer end an upwardly extending cylindrical bearing extending its full width and rotatably received in the bearing of the adjoining traveler, and each link having at its inner end a downwardly disposed cylindrical bearing extending its full width and rotatably received in a bearing socket at the adjoining end of said lifting block whereby vertical movement will be imparted to the lifting block when the screw is rotated.

2. A jack comprising an elongated base having a bottom and side walls, the side walls having inwardly extending flanges along their upper edges carrying depending lips at their inner edges, a bearing block in said base secured to the bottom thereof midway its length and having its lower portion contacting with side walls of the base and its upper portion reduced in width and extending between the depending lips, travelers in end portions of said base resting upon the bottom thereof and each having its lower portion contacting with side walls of the base and its upper portion reduced in width and extending between the lips, an actuating screw extending longitudinally in said base with its intermediate portion journaled through the bearing block and its end portions journaled through the end walls of the base, portions of the screw between the bearing block and opposite ends of the base being oppositely threaded and engaged through threaded bores of the travelers to impart movement to the travelers in opposite directions longitudinally of the base when the screw is rotated, a lifting block disposed over said bearing block and having its opposite ends recessed to form semicircular bearing sockets extending the full width of the lifting block, said travelers having upper portions of their inner ends also formed with recesses defining bearing sockets extending the full width of each traveler, and links extending longitudinally of said base between the lifting block and travelers and along their sides being provided with depending flanges slidably fitting against the depending lips of side walls of the base and snugly fitting between the lips and reduced upper portions of the travelers and bearing block, ends of the links being formed at their ends with cylindrical bearing sleeves extending their full widths and rotatably received in the bearing sockets of the travelers and lifting block whereby vertical movement will be imparted to the lifting block when the screw is rotated.

GEORGE STEPHEN WHITEHEAD. 70
